UNITED STATES PATENT OFFICE.

CHARLES F. ROOT, OF RAVENNA, OHIO, ASSIGNOR OF ONE-FOURTH TO BYRON O. CONN,
OF MANSFIELD, OHIO.

SAFETY DEVICE.

1,198,277.

Specification of Letters Patent. Patented Sept. 12, 1916.

Application filed March 17, 1915. Serial No. 14,976.

To all whom it may concern:

Be it known that I, CHARLES F. Root, a citizen of the United States of America, residing at Ravenna, in the county of Portage and State of Ohio, have invented certain new and useful Improvements in Safety Devices, of which the following is a specification.

This invention relates to a safety device for machines equipped with a movable work engaging element and an opposing element.

One of the objects of this invention is to provide a machine of the type set forth with means which is attached to and automatically interlocks the movable work engaging element upon contact with any obstruction or resistance such as the hand of the operator, or one of the fingers of the hand.

Further, the invention aims to provide means for interlocking the reciprocating work engaging element which carries a contact member so as to render the work engaging element inoperative if said contact member is resisted or it encounters an obstruction in its path prior to the commencement of the punching, pressing, forming or stamping operation, or in other words, before the reciprocating element is about to enter into actual physical contact with the work.

Another object is to provide means which is sensitive to operation by contact with the finger or hand of the operator, should the finger or hand be in a position subject to injury by the reciprocal work engaging element, without actual injury to the finger or hand.

Further, the invention aims to provide a structure which can be adjusted to operate in connection with material possessed of varying thicknesses.

The primary object of the present invention is to provide means attachable to the reciprocating work engaging element which is spaced apart therefrom and arranged to move in advance of the work engaging element which upon contact with an obstruction extraneous to the work actuates an interlocking mechanism (the contact taking place prior to the work engaging element reaching a pre-determined point in its working movement) to simultaneously and instantly interlock, arrest, and support the

work engaging element and prevent further movement thereof.

A further object is to provide means of interlocking and supporting the weight of the reciprocating work engaging element in such a manner as to prevent the work engaging element from resting upon the fingers or hand of the operator which can be used and automatically operated conjointly with the safety devices shown and described in the applications heretofore filed by me of the type and class shown and described in my parent application filed Jan. 2, 1914, Serial No. 809,805.

The preferable specific means employed to accomplish the objects of this invention comprise a pawl and ratchet wheel mechanism which is secured to the work engaging element, the ratchet wheel being rotated by a correlated pinion which engages a rack bar that is secured to the head of the machine and a releasing rod for the pawl which carries a contact member and is automatically actuated to permit the pawl to engage the ratchet wheel by an obstruction in the path of the contact member.

I attain these and other objects by the mechanism illustrated in the accompanying drawing, in which:

Figure 1 is a front elevation of a conventional type of a staying machine showing the invention applied thereto. Fig. 2 is a side elevation of Fig. 1. Fig. 3 is a cross sectional view of Fig. 2 taken on the line X-X of Fig. 2.

In the drawings, reference numeral 1 depicts the bed, 2 an L-shaped bracket, 3 the driving shaft and 4 the driving pulley of a conventional type of a staying machine. The bracket 2 is provided with a head 4 having gib 5 formed thereon to receive for reciprocation therein a work engaging element 6 which carries a die 7 which is adapted to coöperate with an anvil or opposing element 8 for exerting a pressure upon interposed work.

The work engaging element is connected to the driving shaft for reciprocation by a link 9 through the medium of the crank pin 10 and stud 11. A plate 12 having outwardly extending ear portions 13 and 14 is preferably attached to the work engaging element by the bolts 15. Stud shafts 16 and 17 are journaled in ear portions 13 and 14 of

the plate 12 and their ends project therefrom in a horizontal plane.

- Pinions 18 and 19 are rigidly secured to one end of the stud shafts and are located 5 between the gib 5 and the plate 12, the other end of the stud shafts having ratchet wheels 20 and 21 rigidly secured thereto. A portion of the teeth of the ratchet wheels are omitted leaving a plane surface upon 10 part of the periphery thereof. The pinions 18 and 19 engage the teeth of the rack bars 22 and 23 and rotate the ratchet wheels 20 and 21 when the work engaging element is reciprocated. A pawl releasing rod 24 has 15 one end slidably fitted in an aperture formed in the die 7 and carries a contact member 25. The other end of the rod is slidably fitted and guided in a cap bearing 26.
- 20 Pawls 27 and 28 are pivotally mounted upon the work engaging element and are provided with fingers 29 and 30 to engage the block 31. The block 31 is adjustably fitted to the pawl releasing rod 24 to provide 25 means of varying the relation of the pawls with reference to the teeth of the ratchet wheel. A collar 32 is fitted to the pawl releasing rod to permit the rod to be adjusted to support the contact member 30 spaced apart at varying distances from the work engaging element when it is traveling upon its working movement.
- 35 The operation of the mechanism is as follows: When movement is imparted to the driving shaft 3, it reciprocates the work engaging element and the pinions are partially rotated because of their engagement with the teeth of the racks and the pinions in turn partially rotate the ratchet wheels.
- 40 The pawl releasing rod which is pivotally secured to the work engaging element carries the contact member which is spaced apart from the die 7 leaving a space *a* between the work engaging element and said die. The ends of the pawls 27 and 28 are 45 normally held in a position to clear but in close proximity to the teeth of the ratchet wheels by the contact block 31 which is adjustably fitted to the rod and adapted to engage the fingers 29 and 30 of the pawls and normally prevent them from dropping by gravity. If no obstruction is encountered by the contact member or it is not resisted before it reaches a pre-determined point in 50 its working movement, the work engaging element will force the contact member to act upon the work. The engagement of the pinions with the racks and the correlated relation of the teeth of the ratchet wheels 55 are such that the pinions will rotate the ratchet wheels carrying the teeth thereof beyond the ends of the pawls when no obstruction is encountered by the contact member before the work engaging element reaches a 60 predetermined point in its working move-

ment, so that when the pawls drop by gravity they will contact with and slide over the plane surface *b* of the ratchet wheels and therefore can not engage the teeth of the ratchet wheels. If the contact member 70 is resisted or encounters an obstruction extraneous to the work before the work engaging element reaches a predetermined point in its working movement, the rod 24 will be arrested while the work engaging 75 element will continue its movement closing the intervening space *a* between the die 7 and contact member 28 and at the same time changing the relation of the contact block 31 (as shown in dotted lines, Fig. 1) with 80 reference to the fingers of the pawls, thereby permitting the pawls to drop by gravity and engage the teeth of the ratchet wheels, securely locking, supporting and preventing further movement of the work engaging element. 85

In practice the ratchet wheels are rotated by the pinions to present the plane surfaces thereof underneath the pawls when the work engaging element has reached a predetermined point in its working movement, which point is preferably located about $\frac{1}{8}$ of an inch from the end of the working movement of the work engaging element. When an obstruction extraneous to the work is encountered by the contact member such as the fingers or hands of the operator or the bar *c*, the releasing bar is actuated to release the pawls and they drop by gravity and engage the teeth of the ratchet wheels as shown in 95 dotted lines, Fig. 1.

Duplicate pawl and ratchet mechanisms are preferably used to accomplish the objects herein referred to but it will be apparent to those skilled in the art that a single ratchet 105 mechanism can be used or a train of pawls and ratchet wheels can be used to provide for finer adjustment of the parts if desired and other immaterial changes may be made without departing from the principle or 110 spirit of my invention.

What is claimed is:

1. In a safety device for machines equipped with coöperating pressure elements, one of said elements being movable toward the 115 other, stationary racks, a pawl and ratchet mechanism which engages the racks, and means carried by the movable element operable by pressure to actuate the pawls to lock and support the movable element. 120
2. In a machine of the class described, the combination with two opposing elements coöperative to exert a pressure upon interposed work and one of which elements is movable toward and from the other, an actuating means for said element, means carried by said movable element and spaced apart therefrom, stationary racks, and means coöperative with the stationary racks to interlock said movable element which is auto- 125 130

matically operable when the means carried by the movable element is resisted before acting on the work.

3. In a machine of the class described, 5 the combination with two opposing elements coöperative to exert pressure upon interposed work and one of which elements is movable toward and from the other, an actuating means for said movable member, of 10 normally inoperative means for interlocking, supporting and preventing movement of the movable element, and means carried by the movable element, a part of which travels in advance of the movable element, 15 and which automatically actuates the locking means to interlock the movable element upon said part meeting resistance.

4. The combination with a reciprocating member to act upon the work and means to 20 actuate said member, of automatic means associated with said member, a part of which travels in advance of the reciprocating member, stationary racks, a pawl and a ratchet mechanism cooperating with said stationary 25 racks whereby said member is interlocked, supported and prevented from further movement during its operative stroke when said part contacts with an obstruction extraneous to the work before it reaches a pre- 30 determined point in its operative stroke.

5. In combination with a movable work 35 engaging element to act on the work and means to actuate said member, an interlocking mechanism carried by said element which is normally inoperative, stationary racks to engage said locking mechanism and means carried by the movable element and spaced apart therefrom to automatically actuate the interlocking means to support and 40 prevent movement of the movable work engaging element if an obstruction is encountered before the work engaging element reaches a pre-determined point in its working movement.

45 6. In combination with a reciprocating element to act upon the work and means to actuate said element, an interlocking mechanism normally held inoperative comprising a pawl and ratchet mechanism, pinions 50 associated with the pawl and ratchet mechanism, racks to engage the pinions and impart movement thereto when the reciprocating element is actuated, means to automatically actuate the interlocking means to interlock the reciprocating element on the operative stroke of said element when the path of the element is obstructed before it reaches a predetermined point in its working stroke.

7. In combination with reciprocating 60 means to act upon the work, stationary racks, interlocking means engaging the racks and carried by the reciprocating means; said interlocking means being normally inoperative and capable of being maintained inoperative when the path of the reciprocating

means is free, yieldable means associated with the interlocking means to lock the reciprocating means and prevent movement thereof upon engagement of the yieldable associated means with an obstruction before it reaches a pre-determined point in its working movement. 70

8. In combination with a reciprocating element and its actuating means, a safety locking mechanism normally inoperative 75 carried by said element, a releasing rod movably mounted upon said element, a contact member connected to said releasing rod and spaced apart from the reciprocating element; said contact member being automatically operated to actuate the safety mechanism to lock the reciprocating element and prevent movement thereof when the contact member encounters an obstruction extraneous to the work. 80

85 9. The combination with the reciprocating working member of a machine, of a safety device comprising a pawl and ratchet normally inoperative locking mechanism which is mounted on the reciprocating working member, means carried by the reciprocating member, a part of which travels in advance thereof and which automatically actuates the pawl and ratchet mechanism to interlock and support the reciprocating 90 working member if said part is resisted before it reaches a pre-determined point in its working movement. 95

10. The combination with a work performing element and its actuating means, of 100 a locking mechanism mounted on the work performing element which is normally inoperative, stationary racks to actuate the locking mechanism, means connected to the locking mechanism for controlling it which 105 travels in advance of the work performing element on its working stroke, and which is automatically operable if resisted before it reaches a pre-determined point in its travel to actuate the locking mechanism to interlock the work performing element. 110

11. In a machine of the class described, the combination with two opposing elements coöperative to exert a pressure upon interposed work and one of which elements is 115 movable toward and from the other, and actuating means for said movable element, a yielding rod carrying a contact piece, of locking means carried by said movable element to render the movable element inoperative upon resistance being offered to the contact piece prior to its acting upon the work. 120

12. The combination with a work performing element and its actuating means, of 125 locking means mounted upon the work performing element, stationary racks to actuate said locking mechanism; means carried by but spaced apart from the work performing element and connected to the locking mechanism which automatically operates the lock- 130

ing mechanism to lock the work performing element if resistance is offered to said last mentioned means prior to its acting upon the work.

- 5 13. In a safety device for machines of the class described, in combination with the co-operative pressure elements thereof, a locking mechanism carried by the movable element which is normally inoperative, means 10 to impart movement to the locking mechanism, a yielding member which forms part of the working face of the movable element that is operable by pressure to cause the locking mechanism to lock and support the 15 movable element at a pre-determined point in its working movement.

14. In a safety device for machines equipped with co-operative pressure elements,

one of which is under normal conditions movable toward and from the other, a locking 20 mechanism to prevent movement of the movable element on its working stroke under abnormal conditions, means forming part of the working face of the movable element for controlling the locking mechanism 25 which is carried by the movable element, and is operable by an extraneous obstruction to permit the locking mechanism to interlock with the movable element to support and prevent further movement thereof.

In testimony whereof I affix my signature in presence of two witnesses.
